COMBINED ASH TRAY, COMPASS, SUNDIAL, AND BILLBOARD OR SIMILAR ARTICLE

Seth S. Pace, Staten Island, N. Y.

Application February 13, 1951, Serial No. 14,196

Term of patent 14 years

(Cl. D85—2)

To all whom it may concern:

Be it known that I, Seth S. Pace, a citizen of the United States, and residing at Staten Island, New York city, New York, in the county of Richmond, have invented a new, original, and ornamental Design for a Combined Ash Tray, Compass, Sundial and Bill Board or Similar Article, of which the following is a specification, reference being had to the accompanying drawing, forming a part hereof, and in which,

Fig. 1 is a perspective view of a combined ash tray, compass, sundial and bill board or similar article, showing my new design;

Fig. 2 is a side elevational view thereof;

Fig. 3 is a front elevational view thereof; and
Fig. 4 is a bottom plan view thereof, on a reduced scale.

The dominant features of my new design are shown in solid lines in the drawing.

I claim:

The ornamental design for a combined ash tray, compass, sundial and bill board or similar article, substantially as shown and described.

SETH S. PACE.
